UNITED STATES PATENT OFFICE.

THOMAS S. FITCHETT, OF GLENARM, AND JØRGEN I. HAASE, OF TOWSON, MARYLAND,
ASSIGNORS TO F. X. HOOPER COMPANY, INC., OF GLENARM, MARYLAND, A COR-
PORATION OF MARYLAND.

INKING ATTACHMENT FOR CYLINDER PRESSES.

Application filed February 6, 1922. Serial No. 534,471.

To all whom it may concern:

Be it known that we, THOMAS S. FITCHETT and JØRGEN I. HAASE, respectively a citizen of the United States and a subject of the 5 King of Denmark, residing at Glenarm and Towson, respectively, in the county of Baltimore and State of Maryland, have invented certain new and useful Improvements in Inking Attachments for Cylinder 10 Presses, of which the following is a specification.

This invention relates to roller inking attachments for cylinder printing presses, and it comprises means whereby the several 15 composition and hard rollers may be readily separated or brought together. When the press is idle, it is desirable to keep the composition rollers out of contact with the hard rollers in order that the surfaces of the composition rollers may not become flattened or 20 indented along the lines of contact with the hard rollers. In carrying out the invention, as illustrated in the drawing, the composition form rollers, ink fountain and fountain 25 roller are arranged on a stationary frame to which is hinged a main rocking frame carrying metal vibrating rollers, adapted to engage the form rollers, and also carrying a distributing roller. The rollers on this rocking frame are connected by a gear train, 30 one member of which is adapted to mesh with a driving gear on the stationary frame when the parts are in their working positions. This main rocking frame is movable 35 about its axis, to carry the vibrating rollers out of contact with the form rollers. Upon the main rocking frame is hinged a secondary rocking frame which carries composition rollers, each adapted to engage the 40 distributing roller and one of said vibrating rollers, and this secondary frame is movable with respect to said main rocking frame to carry said composition rollers out of engagement with the distributing and vibrating 45 rollers. A ductor roller, which operates in the usual way to transfer the ink from the fountain roller to the distributing roller, is mounted on the main rocking frame and moves with the latter so that when the rocking frames are moved to separate the hard 50 and composition rollers, the ductor roller will be moved to a position where it will not interfere with or be engaged by the

composition rollers on the secondary frame.

In order to move the rocking frames to 55 and from their working positions, we provide upon the stationary frame a segmental rack, curved in the arc of a circle concentric with the axis of the main rocking frame, and we also provide a segmental rack 60 upon the secondary rocking frame, curved in the arc of a circle concentric with the axis of said latter frame, and these racks are engaged by gears upon a shaft which is mounted in the main rocking frame and 65 operating by a hand wheel. When this shaft is turned, the rocking frames swing about their axes simultaneously. If the shaft is turned in one direction, all of the rollers will be brought into their working positions, and if the shaft is turned in the opposite direction, the hard and composition 70 rollers will be separated. By suitable locking means associated with the hand operating shaft, the rocking frames may be locked 75 in either operative or inoperative positions.

In the accompanying drawing,

Fig. 1 is an end elevation of the inking mechanism, portions of the form cylinder and driving gear also being shown, the 80 rollers being shown in their working positions;

Fig. 2 is a similar view, showing the composition rollers separated from the hard or metal rollers;

Fig. 3 is a rear elevation of the inking mechanism, looking from left to right in Fig. 1;

Fig. 4 is a side view of one of the plates or brackets forming part of the stationary 90 frame which supports the inking mechanism;

Fig. 5 is a similar view of one of the plates forming part of the rocking frame which carries the distributing and vibrating 95 rollers;

Fig. 6 is a similar view of one of the plates forming part of the rocking frame which carries the intermediate composition rollers and the ductor roller; and,

Fig. 7 is a detail view showing the locking device for the shaft by which the rocking frames are moved to engage and disengage the composition rollers from the metal rollers.

Referring to the drawing, *a* represents the

form cylinder of a printing press, *b* indicates a stationary frame which is secured by bolts 1 to arms 2, which project from the bearings in which the form cylinder is mounted. The frame *b* comprises two side plates or brackets 3, having the form shown in Fig. 4, and these side plates are connected at their upper ends by the ink fountain 4 which they support. Composition form rollers 5, 6, 7, and 8 are mounted in suitable bearings in the bracket *b*, the bearings 9 for one of the rollers being shown in Fig. 3, and the bearings for the other rollers being omitted for the sake of clearness. The frame *b* also carries at its upper end a fountain roller 10 for feeding the ink from the fountain, and this roller is operated in the usual way by ratchet mechanism 11 upon the shaft 10^b of said roller, (Fig. 3) to feed the ink from the fountain. The end plates 3 of the frame *b* each have downwardly and rearwardly extending arms 3^a to which are pivotally connected the end plates 12 of a frame *c*. As shown, each plate 12 has a downwardly extending arm 12^a, the end of which is connected to the downward extension of the adjacent plate 3 by a pivot pin or stud 13. The plates 12 have forward extensions 12^b, and the plates 30 are connected together by a rod 14, passing through said extensions. The frame *c* has suitable bearings in which are mounted the shafts of metal vibrating rollers 15 and 16 and a distributing roller 17. The vibrating roller 15 is adapted to engage the form rollers 5 and 6, and the vibrating roller 16 is adapted to engage the form rollers 7 and 8. These several rollers are connected by a gear train, as shown, consisting of the gears 18, 19, 20, 21, and 22, the gears 19 and 21 being idle gears. In the working position of the parts, the gear 22 engages a driving gear 23 which is mounted upon the stationary frame *b* and meshes with a large gear 24 which rotates with the form cylinder. The rocking frame *c* also carries at its upper end the rock shaft 25, upon which the arms 26, which support the ductor roller 27, are mounted, the bearings for said shaft being indicated at 28. The end plates of the frame *c* are also provided with bearings 29 for a shaft 30, which is rotatable in said bearings by means of a hand wheel 31. This shaft carries, near its opposite ends, 55 pinions 32 which engage segmental racks 33, secured to the end plates of the stationary frame *b*, said racks being curved in the arc of a circle concentric with the axis of the studs 13 about which the frame *c* rocks. With this arrangement, by turning the hand wheel in the left-handed or counter-clockwise direction, in Fig. 1, the pinions will move along the racks 33 and the frame *c*, in which the shaft 30 is mounted, 60 will be rocked about the studs 13 and the

metal rollers on said rocking frame will be moved out of engagement with the form rollers, as illustrated in Fig. 2.

A second rocking frame *d* is pivoted to the frame *c* and carries composition rollers 70 34 and 35, the former of which is adapted 75 to engage the distributing roller 17 and vibrating roller 15, and the latter of which is adapted to engage said distributing roller and the vibrating roller 16. This frame *d* 80 comprises two end bars or plates 36, one of which is shown in detail in Fig. 6, these plates having bearings 36^a at their forward ends by which they are journaled upon the rod or shaft 14. The rear ends of plates 85 36 are provided with segmental racks 37, concentric with the shaft 14, and these racks are engaged by gears 38 upon the manually operable shaft 30. The racks 33 and 37 on the frames *b* and *d* are substantially at 90 right angles to one another, and when the hand wheel 31 is moved as before described, to rock the frame *c* rearwardly, the frame *d* by the same movement will be rocked upwardly and the intermediate composition rollers 95 34 and 35 on the latter frame will be moved away from the metal rollers on the frame *c*, as shown in Fig. 2. As the frame *c* is rocked rearwardly, the ductor roller 27, which is carried by said frame, is moved rearwardly 100 out of the way of the intermediate composition roller 35 which swings toward the fountain roller 10. When the hand wheel is turned in the clockwise direction, the pinions 32 roll along the racks 33 and return 105 the frame *c* to its working position and the gears 38 simultaneously lower the frame *d* to its working position wherein the various composition rollers are engaged by the metal rollers and the ductor roller is in position 110 to vibrate between the fountain roller and the distributing roller.

The rocking frames may be locked in their operative or inoperative positions by suitable means. In Fig. 7, the locking means 110 employed is shown in detail. The hand wheel is keyed to the end 30^a of the shaft 30, and is slidable thereon, and also has a threaded extension 30^b, on which is fitted a nut 39. By loosening the nut 39, the hand 115 wheel may be moved away from the bearing 40. The hub of the hand wheel is provided with an extension 41, in which is secured a pin 42, adapted to enter any one of a series of openings 43 (Fig. 5) in an enlargement of the bearing 40. By loosening the nut 39, the hand wheel may be moved 120 outwardly to withdraw the pin from any opening with which it may have been engaged, and by then turning the wheel the 125 frames will be rocked to the desired positions. The hand wheel may then be pressed toward the shaft bearing to engage the pin with another opening in the bearing. By tightening the nut 39, the wheel will be 130

held in place against the bearing and the frames will be locked.

By the mechanism described, all of the rollers can be held positively out of engagement, and brought back positively into exact alignment positions. This, as will be evident, is an improvement over the ordinary method of mounting the rollers, whereby the rollers are lifted individually to 10 their disengaging positions and allowed to drop by gravity to their engaging positions.

For conveniently distinguishing the rocking frames in the claims, I have termed the frame *c*, which carries the metal rollers, a 15 main rocking frame, and the frame *d* a secondary rocking frame.

What we claim is:

1. In an inking attachment for printing presses, a stationary frame, a pair of composition form rollers thereon, a main rocking frame hinged to the stationary frame, a distributing roller and a vibrating roller on said main rocking frame, said vibrating roller adapted to engage the form rollers, 25 a gear train connecting the rollers on said main rocking frame, a secondary rocking frame hinged to said main rocking frame, a composition roller on said secondary frame adapted to engage the distributing and vibrating rollers, and means for swinging said rocking frames about their axes.

2. In an inking attachment for printing presses, a stationary frame, a pair of composition form rollers thereon, a main rocking frame hinged to the stationary frame, a ductor roller, a distributing roller and a vibrating roller on said main rocking frame, said vibrating roller adapted to engage the form rollers, a gear train connecting the 35 rollers on said main rocking frame, a secondary rocking frame hinged to said main rocking frame, a composition roller on said secondary frame adapted to engage the distributing and vibrating rollers, and means 40 for swinging said rocking frames about their axes.

3. In an inking attachment for printing presses, a stationary frame, a pair of composition form rollers thereon, a main rocking frame hinged to the stationary frame, a distributing roller and a vibrating roller on said main rocking frame, said vibrating roller adapted to engage the form rollers, a gear train connecting the rollers on said 50 main rocking frame, a secondary rocking frame hinged to said main rocking frame, a composition roller on said secondary frame adapted to engage the distributing and vibrating rollers, means for swinging said

rocking frames about their axes, and means 60 for locking said rocking frames in their operative and inoperative positions.

4. In an inking attachment for printing presses, a stationary frame, a pair of composition form rollers thereon, a main rocking frame hinged to the stationary frame, a distributing roller and a vibrating roller on said main rocking frame, said vibrating roller adapted to engage the form rollers, a gear train connecting the rollers on said 65 main rocking frame, a secondary rocking frame hinged to said main rocking frame, a composition roller on said secondary frame adapted to engage the distributing and vibrating rollers, and means for swinging said 70 rocking frames about their axes comprising a rack on said stationary frame concentric with the axis of the main rocking frame, a rack on said secondary rocking frame concentric with the axis of the latter, a shaft 75 journaled in said main rocking frame, and gears on said shaft engaging said racks.

5. In an inking attachment for printing presses, a stationary frame, a plurality of form rollers thereon, a main rocking frame 85 hinged to said stationary frame, a distributing roller and a plurality of vibrating rollers on said latter frame, said vibrating rollers each adapted to engage a pair of form rollers, a gear train on said main rocking 90 frame connecting said distributing and vibrating rollers, a secondary rocking frame hinged to said main rocking frame, composition rollers on said secondary frame each adapted to engage the distributing 95 roller and one of said vibrating rollers, and means for swinging said rocking frames about their axes to disengage the composition rollers from their co-acting 100 rollers.

6. In an inking attachment for printing presses, a stationary frame, composition form rollers thereon, a main rocking frame hinged to the lower rear part of said stationary frame and extending forwardly 105 thereof, said rocking frame having distributing and vibrating rollers, a secondary rocking frame hinged to the forward part of said main rocking frame and extending rearwardly, said secondary frame having 110 composition rollers thereon, and means for simultaneously moving said rocking frames about their axes.

In testimony whereof we affix our signature.

THOMAS S. FITCHETT.
JORGEN I. HAASE.
